CLAIM

The ornamental design for a bracket for accommodating a night vision unit, as shown.

DESCRIPTION

FIG. 1 is a front perspective view of a bracket for accommodating a night vision unit showing my new design;
FIG. 2 is a front elevational view thereof;
FIG. 3 is a top plan view thereof;
FIG. 4 is a right side elevational view thereof;
FIG. 5 is a left side elevational view thereof;
FIG. 6 is a rear elevational view thereof; and,
FIG. 7 is a bottom plan view thereof.

The broken line showing of the headband and night vision unit in FIG. 1 is for illustrative purposes only and forms no part of the claimed design.
